KNOCK-DOWN DISPLAY DEVICE

Nathan Joseph Leigh, Great Neck, N. Y., assignor
to Eimson-Freeman Co., Inc., Long Island City,
N. Y., a corporation of Delaware

Application March 31, 1936, Serial No. 71,886

15 Claims. (Cl. 40—126)

My present invention relates generally to display signs, and has particular reference to a knockdown display device.

An object of the invention is to provide an improved advertising display device composed solely of cardboard or its equivalents, the structure being of a character which permits the device to be inexpensively manufactured from flat cardboard stock, and to be conveniently set up into display condition.

One of the features of my present device resides in its improved rigidity and staunchness, and in the ability to simulate a three-dimensional display of considerable thickness and weight, notwithstanding the fact that the device is actually composed only of sheet cardboard or the like.

The present improved device consists essentially of a front panel, in association with trapezoidal border panels hinged to the edges of the front panel and adapted conjointly to define a beveled border for the device as a whole. A feature of the invention lies in the fact that means are provided in concealed position behind the beveled border for releasably interlocking and bracing the trapezoidal panels in set-up condition. Preferably, the bracing means consists of interengageable flaps hinged to the outer edges of the trapezoidal panels, whereby the front panel, the trapezoidal panels, and the attachment flaps may all consist of integral parts of a single cardboard blank.

The present device lends itself admirably to an advertising display of silhouette type. Thus, in a preferred embodiment, the front panel has predetermined portions cut out to define a silhouette depiction, and a concave reflector is mounted behind the depiction to serve as a background therefor, the reflector consisting of a blank of flexed cardboard whose exposed surface is composed of colored metallic foil.

The combination of the concave background for the silhouette display, with the beveled border, produces a highly desirable effect of depth and thickness.

I achieve the foregoing objects, and such other objects as may hereinafter appear or be pointed out, in the manner illustratively exemplified in the accompanying drawings, wherein—

Figure 1 is a perspective view of a display device constructed in accordance with my present invention;

Figure 2 is an enlarged cross-sectional view taken substantially along the line 2—2 of Figure 1;

Figure 3 is a rear view of the device in collapsed condition;

Figure 4 is a fragmentary rear view showing one manner in which the attachment flaps may be caused to interengage;

Figure 5 is a fragmentary rear view of a portion of the prop for the device;

Figure 6 is a rear perspective view of a slightly modified construction;

Figure 7 is a fragmentary plan view of the 10 corner of the blank of which the device of Figure 6 is composed;

Figure 8 is a view similar to Figure 7, showing the device in partly set-up condition;

Figure 9 is a cross-sectional view taken substantially along the line 9—9 of Figure 8;

Figure 10 is a view similar to Figure 8, showing the device in fully set-up condition; and

Figure 11 is a cross-sectional view taken substantially along the line 11—11 of Figure 10.

Referring to Figures 1—5, a front panel 10 has predetermined portions cut out to define a desired silhouette depiction 11. The reference numerals 12 are applied to certain edges of the cut-out portions, and it will be observed that three of these edges define the major portion of a substantially rectangular aperture. The effectiveness of the depiction is enhanced by printing lines 13 on the front panel, these lines forming continuations of certain of the edges 12 so as to create the effect of a substantially rectangular aperture with the depiction 11 behind it.

Desired advertising indicia, such as indicated by the reference numeral 14, and other ornaments or the like are also printed or lithographed on the front face of the front panel 10.

Hinged to the edges 15 of the front panel are trapezoidal panels 16, the end edges of which are all of equal lengths. This permits the panels 16 to be folded rearwardly, as indicated in Figures 1 and 2, so that the end edges arrange themselves in registering relation, whereby the panels 16 conjointly define a beveled frame or border for the device.

One way of securing the device in set-up condition is illustrated in Figures 2, 3, and 4. Flaps 18 are hinged to the outer edges 19 of the panels 16. At their opposite ends the flaps 18 are provided with hooked portions 20 and 21, or with any equivalent interengageable means, so that each end of each flap 18 may be releasably interlocked or interengaged with the adjacent end of the adjacent flap, as shown most clearly in Figure 4.

When the flaps 18 are all interengaged, they are disposed in a substantially single plane parallel 55

to the plane of the front panel 10, as shown most clearly in Figure 2. In this way they serve as an efficient brace for the entire device and serve the dual function of interlocking the trapezoidal panels 16 in set-up condition, and also bracing the structure.

As will be observed from Figure 3, the front panel 10, the trapezoidal panels 16, and the flaps 18 may form parts of a single blank of card-board or the like. This results in great economy of manufacture and permits the device to be stacked and shipped in substantially flat condition. At the same time, it may be set up with considerable ease by merely bending the panels 16 rearwardly, and bending the attachment flaps 18 rearwardly and into the interengaged relationship shown in Figures 1, 2, and 4. Preferably, though not necessarily, the panels 16 are colored in a distinguishing way so that they form an ornamental beveled border for the structure, imparting to it an effect of depth and staunchness which only a structure of much more rigid and substantial material would otherwise produce.

25 While, from certain aspects, the device is useful without any silhouette depiction in the front panel, the beveled border is admirably suited to cooperate with an advertising display of the character illustrated, whereby a concave reflector is positioned behind the silhouette depiction to 30 serve as a background therefor.

In the construction illustrated in the drawings, it will be observed that a blank of flexed cardboard 22, whose exposed or front surface is composed of colored metallic foil, is hingedly secured, 35 as at 23, to the rear surface of the panel 10. The opposite edge of the blank 22 is braced in position by engagement beneath an abutment 24. The latter consists of a blank of cardboard adhesively secured to the rear of the panel 10, with 40 one portion free of attachment and hence adapted to serve as an abutment, as shown in Figure 2.

In the illustrated embodiment, the blank 22 is flexed into conformity with a cylindrical surface, and the opposite edges of the blank, at 23 and at 24, are held in engagement with the panel 10 adjacent to opposite lateral edges of the depiction 11, i. e., adjacent to opposite lateral edges 12 of the substantially rectangular aperture shown. When the device is shipped or stacked, the free edge 50 of the blank 22 is released from beneath the abutment 24 and may then lie perfectly flat against the back of the panel 10. When the device is set up, this free edge is merely fitted beneath the abutment 24, and this serves not only to flex the blank 22 but also to hold it in such relationship.

60 The construction is completed by the provision of one or more props, and I have illustratively shown a blank of cardboard 25 which is cut out, as at 26, to provide a brace 27. The blank 25 has a portion 28 which is adhesively secured to the back of the panel 10, and the free portion 29 may then be folded down flat, as shown in Figure 3, or it may be bent at right angles, as shown in Figure 5, when the device is set up. Similarly, the brace 27 fits into the position shown in Figure 5 when the device is set up, or it may be folded up into the plane of the portion 28 when the device is collapsed.

70 Obviously, the invention is not restricted to any particular depiction nor to the provision of an aperture in the panel 10. The latter may, for example, be unapertured and whole; and where cut-outs are desired, they may, obviously, assume any desired form, depending upon requirements.

Similarly, while I have shown the device as a whole as being of substantially rectangular form, it will be understood that a triangular or other polygonal contour may be provided for, depending upon the uses to which the device is to be put and the display effect which is desired. 5

In Figures 6-11, I have illustrated a modified construction in which the front panel 30 is unapertured and in which the bracing flaps 31 and 32 are interengaged in a different manner. The 10 device is preferably formed of a single blank of cardboard or the like shaped and cut to define the front panel 30, the trapezoidal panels 33, and the bracing flaps 31 and 32. I have also shown the manner in which a prop 34 may be integrally 15 formed with respect to the other elements of the device, this prop being connected along the hinge line 35 to the outer edge of one of the flaps 32. A prop brace 36 is provided, and this brace may be the same as the brace 27 illustrated in Figures 20 3 and 5.

The means for interengaging the bracing flaps 31 and 32 is illustrated most clearly in Figures 7-11. At each end of each flap 32 I provide a slot 37, and at each end of each flap 31 I provide a tab adapted to cooperate with the slot 37. The tab has a body portion 38 and a lateral latching portion 39 hinged to the body portion along the line 40. After the blank has been cut out and scored, as indicated in Figure 7, the lateral portion 39 of the tab is folded along the line 40 into superposed relation to the body portion 38. The flaps 31 and 32 are then bent rearwardly so that they lie in a plane substantially parallel to the front panel 30. The tab is then inserted 35 into the slot 37, as shown in Figure 8, and it is to be noted that the tab is purposely made sufficiently long so that it may engage with the slot 37 even while the device is in the substantially flat condition of Figures 8 and 9. In this condition, it will be noted, the trapezoidal panels 33 lie substantially in the plane of the front panel 40

Preferably, the device is shipped to the user in the condition shown in Figures 8 and 9. This leaves nothing further to be done except to push the tab further into the slot 37. As soon as the tab is pushed into the slot to its fullest extent, the latching portion 39 automatically spreads away from the body portion 38 and assumes a position somewhat as shown in Figures 10 and 11. This locks the tab within the slot and thus automatically interengages each flap with the adjacent flap, thereby firmly retaining the device in fully set-up condition. 55

The reason why the portion 39 of the tab automatically spreads, as described in the preceding paragraph, is that the cardboard material has a certain inherent resilience, whereby the portion 39 yieldably resists the action of the slot 60 37 in Figure 8 in holding the portions 38 and 39 in superposed relation. Accordingly, as soon as the portion 39 is free to move, as it is when the tab is pushed into the slot to its fullest extent, it springs or spreads away from the portion 38, 65 as hereinbefore described.

The interengaging hooks 20 and 21 of the embodiment of Figures 1-5 are well adapted for use where the cardboard stock is relatively heavy. Where the cardboard stock is relatively thin, 70 such as the material known in the trade as "30-point", the construction of Figures 6-11 is not only preferable, but highly advantageous.

One of the outstanding advantages of the present construction lies in its rigidity. For exam- 75

ple, a panel of the 30-point stock, having a size approximately fourteen inches by twenty inches, is not particularly rigid and is quite flexible. The same panel, however, when provided with the 5 trapezoidal border panels, as shown in Figures 6-11, and with the bracing flaps 31 and 32 (all composed of the same integral blank), assumes an unusual amount of rigidity, so that the finished structure constitutes a highly presentable 10 and attractive display device of remarkable stiffness.

In general, it will be understood that changes 15 in the details, herein described and illustrated for the purpose of explaining the nature of my invention, may be made by those skilled in the art without departing from the spirit and scope of the invention as expressed in the appended claims. It is, therefore, intended that these 20 details be interpreted as illustrative, and not in a limiting sense.

Having thus described my invention, and illustrated its use, what I claim as new and desire to secure by Letters Patent is—

1. A cardboard knockdown display device 25 comprising a front panel, trapezoidal panels hinged to the edges of the front panel and adapted conjointly to define a beveled border for the device, and means concealed behind said beveled border for releasably interlocking and bracing 30 said trapezoidal panels in set-up condition.

2. A cardboard knockdown display device comprising a front panel, trapezoidal panels hinged to the edges of the front panel, the end edges of said trapezoidal panels being of equal 35 lengths, whereby said panels are adapted to define a continuous beveled border for the device, and means concealed behind said beveled border for releasably interlocking and bracing said trapezoidal panels in set-up condition.

3. A cardboard knockdown display device 40 comprising a front panel, trapezoidal panels hinged to the edges of the front panel and adapted conjointly to define a beveled border for the device, and interengageable flaps hinged to the outer edges of said trapezoidal panels for retaining 45 and bracing the latter in set-up condition.

4. A cardboard knockdown display device comprising a front panel, trapezoidal panels hinged to the edges of the front panel and adapted 50 conjointly to define a beveled border for the device, and interengageable flaps hinged to the outer edges of said trapezoidal panels for retaining and bracing the latter in set-up condition; said front and trapezoidal panels and said 55 flaps being integral portions of a single blank adapted to be collapsed into a single plane.

5. A cardboard knockdown display device comprising a front panel certain portions of which are cut out to define a silhouette depiction, 60 trapezoidal panels hinged to the edges of the front panel and adapted conjointly to define a beveled border for the device, means concealed behind said beveled border for releasably interlocking and bracing said trapezoidal panels in set-up condition, and a concave-reflector mounted 65 on the rear of the front panel to serve as a background for said depiction.

6. A cardboard knockdown display device comprising a front panel certain portions of which 70 are cut out to define a silhouette depiction, trapezoidal panels hinged to the edges of the front panel and adapted conjointly to define a beveled border for releasably interlocking and bracing said trapezoidal panels in set-up condition, and a concave reflector mounted on the rear of the 75

front panel to serve as a background for said depiction, said reflector comprising a flexed cardboard blank secured to the front panel adjacent to the edges of said depiction, said cardboard blank having its exposed surface composed of 80 colored metallic foil.

7. A cardboard knockdown display device comprising a front panel certain portions of which are cut out to define a silhouette depiction, trapezoidal panels hinged to the edges of the front 10 panel and adapted conjointly to define a beveled border for the device, means concealed behind said beveled border for releasably interlocking and bracing said trapezoidal panels in set-up condition, and a concave reflector mounted on the 15 rear of the front panel to serve as a background for said depiction, said reflector comprising a blank of cardboard having its exposed surface composed of colored metallic foil, said blank being flexed into conformity with a cylindrical surface, 20 one edge of said blank being hingedly secured to the front panel, and an abutment carried by the front panel for releasably bracing the opposite edge of said blank.

8. A cardboard knockdown display device 25 comprising a front panel, trapezoidal panels hinged to the edges of the front panel and adapted conjointly to define a beveled border for the device, and means concealed behind said beveled border for releasably interlocking and bracing said trapezoidal panels in set-up condition, said means comprising flaps hinged to the outer edges of said trapezoidal panels and adapted to be folded into a plane substantially parallel to the front panel, and means at the opposite ends of each flap for 30 permitting releasable engagement of each end with the adjacent end of the adjacent flap.

9. A cardboard knockdown display device comprising a front panel, trapezoidal panels hinged to the edges of the front panel and adapted 40 conjointly to define a beveled border for the device, bracing flaps hinged to the outer edges of said trapezoidal panels and arranged behind said beveled border in a plane substantially parallel to the front panel, and means for releasably engaging each flap end with the adjacent end of the adjacent flap.

10. A cardboard knockdown display device comprising a front panel, trapezoidal panels hinged to the edges of the front panel and adapted 50 conjointly to define a beveled border for the device, bracing flaps hinged to the outer edges of said trapezoidal panels and arranged behind said beveled border in a plane substantially parallel to the front panel, and a prop for the device hinged to 55 the outer edge of one of said flaps.

11. A cardboard knockdown display device comprising a front panel, trapezoidal panels hinged to the edges of the front panel and adapted 60 conjointly to define a beveled border for the device, bracing flaps hinged to the outer edges of said trapezoidal panels and arranged behind said beveled border in a plane substantially parallel to the front panel, and a prop for the device hinged to 65 the outer edge of one of said flaps; said front panel, trapezoidal panels, bracing flaps, and prop forming integral parts of a single cardboard blank.

12. A cardboard knockdown display device comprising a front panel, trapezoidal panels hinged to the edges of the front panel and adapted 70 conjointly to define a beveled border for the device, bracing flaps hinged to the outer edges of said trapezoidal panels and arranged behind said beveled border in a plane substantially parallel to the front panel, and means for releasably engag- 75

ing each flap end with the adjacent end of the adjacent flap, said means comprising a slot in one flap end and a tab on the adjacent flap end insertable into said slot, and means for automatically latching said tab in the slot when it is pushed into the slot to its fullest extent.

13. A cardboard knockdown display device comprising a front panel, trapezoidal panels hinged to the edges of the front panel and adapted con-

10 jointly to define a beveled border for the device, bracing flaps hinged to the outer edges of said trapezoidal panels and arranged behind said beveled border in a plane substantially parallel to the front panel, and means for releasably engag-
15 ing each flap end with the adjacent end of the adjacent flap, said means comprising a slot in one flap end and a tab on the adjacent flap end insertable into said slot, said tab being long enough to remain within said slot when the de-
20 vice is collapsed into a substantially flat condition with the trapezoidal panels arranged in the plane of the front panel.

14. A cardboard knockdown display device comprising a front panel, trapezoidal panels hinged to
25 23 the edges of the front panel and adapted con-
jointly to define a beveled border for the device, bracing flaps hinged to the outer edges of said trapezoidal panels and arranged behind said bev-

eled border in a plane substantially parallel to the front panel and means for releasably engag-
ing each flap end with the adjacent end of the adjacent flap, said means comprising a slot in one flap end and a tab on the adjacent flap end insertable into said slot, said tab having a spreadable portion adapted automatically to spread when the tab is pushed into the slot to its fullest extent, thereby latching the tab in the slot.

15. A cardboard knockdown display device com-
prising a front panel, trapezoidal panels hinged to
the edges of the front panel and adapted con-
jointly to define a beveled border for the device, bracing flaps hinged to the outer edges of said trapezoidal panels and arranged behind said bev-
15 eld border in a plane substantially parallel to the front panel, and means for releasably engag-
ing each flap end with the adjacent end of the adjacent flap, said means comprising a slot in one flap end and a tab on the adjacent flap end insertable into said slot, said tab having a body portion and a lateral latching portion hinged to the body portion, said portions being insertable through the slot in superposed relation and the latching portion automatically spreading 25 away from the body portion when the tab is pushed into the slot to its fullest extent.

NATHAN JOSEPH LEIGH.
